UNITED STATES PATENT OFFICE.

CHARLES N. WAITE, OF WILMINGTON, DELAWARE.

DRESS-SHIELD.

No. 874,879.

Specification of Letters Patent.

Patented Dec. 24, 1907.

Application filed November 20, 1906. Serial No. 344,217.

To all whom it may concern:

Be it known that I, CHARLES N. WAITE, residing at No. 806 Adams street, in the city of Wilmington and State of Delaware, have invented certain new and useful Improvements in Dress-Shields, whereof the following is a specification, reference being had to the accompanying drawings.

The object of my invention is to provide a water-proof dress shield which shall be of such a character as to be practically invisible when worn beneath a garment of semi-transparent fabric, such as French nainsook, batiste, or other exceedingly fine material.

15 In the accompanying drawings Figure I represents a dress shield of preferred form, made in accordance with my invention, although, of course, it will be understood that other forms and sizes are comprehended thereby. Fig. II represents, upon an enlarged scale, a piece of the composite fabric of which the shield is made, and Fig. III indicates, upon a still more exaggerated scale, a cross section of said fabric.

25 To construct the fabric from which the shield is made, I take a piece of textile fabric having a relatively open mesh, and composed of relatively fine threads, such for instance as tarlatan, or fine bobbinet, preferably white 30 in color, and I apply thereto a very thin continuous film of cellulose ester in solution, and combined with a softening agent adapted to render it permanently pliable, the solvent and the softening agent employed being such 35 that the applied film shall be substantially transparent and preferably colorless.

I prefer to employ one of the forms of di-nitrocellulose dissolved in ether and alcohol, and to add thereto castor oil as a softening 40 material, but obviously any of the other well-known solvents or softening materials may be employed, provided the resulting film be of the character stated. The cellulose compound may be applied in any convenient 45 manner, but I prefer to pass the fabric through a bath of the dissolved cellulose and to scrape off the excess adhering thereto as it emerges from the bath. I thus obtain, after evaporation of the volatile solvents, a continuous, 50 water-proof, pliable and practically transparent fabric, which, by reason of the supporting medium incorporated therein, will not easily tear or fray.

55 Referring to the drawings, the shield shown in Fig. I consists of two crescent-shaped pieces 1, and 2, secured together at

their concave edges by means of a very thin binding strip 3, which should be as inconspicuous as possible. If the pieces are sewed to the strip, I prefer to apply along the region of the seam a thin solution of the softened cellulose, or I may merely moisten the film at the region with the original solvent. In either case the cellulose will flow sufficiently to close the openings made by the 65 needle and will render the joint substantially water-proof while retaining its pliability.

The general character of the fabric is shown in Figs. II and III, where 5, indicates the layer or film of cellulose, and 4, the 70 threads of the incorporated textile support. It will be noted that owing to the character of the fabric, as a whole, the incorporated medium reduces the liability of the cellulose to tear, and the cellulose tends to prevent 75 the medium from fraying, so that the presence of a binding around the edges is not necessary.

Any desired fastening device can of course be applied to the shield, and the article thus 80 made can be satisfactorily worn beneath the lightest garment, where an ordinary opaque dress shield would be conspicuous by reason of the relative transparency of the garment itself.

85 I have referred to tarlatan and bobbinet as respectively indicating typical woven and netted fabrics which are proper supporting mediums; but, I, of course, do not restrict my claims to any specific fabric, nor to one 90 having any particular color, it being only essential that the incorporated textile fabric should be such as to afford a substantial support to the film, but should not be of such close texture as to be opaque, or be composed 95 of threads so coarse as to be individually conspicuous.

For convenience of description I term the available fabrics, "open mesh fine fabrics", as indicating the desired characteristics of 100 the supporting medium. I employ the term "transparent" in order to appropriately indicate the desired characteristic of my improved dress shield, but it must, of course, be understood that this expression is relative, 105 meaning that the film is one which can be readily seen through, and that the incorporated medium is substantially inconspicuous under the conditions of use.

110 I do not claim broadly the use of a cellulose compound as the material for a dress shield, nor do I claim broadly the application

of a piece of fabric to a layer of such material. The essence of my invention lies in the fact that both the layer itself and the fabric also shall be practically transparent under 5 the conditions of use, and in the further fact that the fabric shall be substantially incorporated in the film, as distinguished from being merely adherent to the exterior thereof.

Having thus described my invention, I 10 claim:—

As a new article of manufacture, a dress-

shield, composed of a film of substantially transparent, softened cellulose ester, provided with an incorporated and inclosed supporting core of open mesh fine fabric. 15

In testimony whereof, I have hereunto signed my name, at Philadelphia, Pennsylvania, this 17th day of November, 1906.

CHARLES N. WAITE.
